(57) **CLAIM**

The ornamental design for a rack for primer tubes and primers for shells, as shown and described.

DESCRIPTION

FIG. 1 is a front elevational view of a rack for primer tubes and primers for shells;

FIG. 2 is a left side elevation view thereof;

FIG. 3 is a top plan view thereof;

FIG. 4 is a bottom plan view thereof;

FIG. 5 is a rear elevation view thereof; and,

FIG. 6 is a perspective view thereof, the broken line disclosure representing primer tubes and a box of primers for shells being for illustrating purposes only forming no part of the claimed design.
